UNITED STATES PATENT OFFICE

2,077,195
CUTLERY GRINDER
Nathan H. Adams, Schenectady, N. Y., assignor
to General Electric Company, a corporation of
New York

Application July 12, 1934, Serial No. 734,778

2 Claims. (Cl. 51—128)

My invention relates to grinders and more particularly to an improved motor driven cutlery grinder for household and other uses.

One object of my invention is to provide a motor driven grinder which will be safe for household use.

Another object of my invention is to provide a guide slot having its sides at different angles to the grindstone so that each side respectively may be used for guiding tools having cutting edges at different angular relation to the guiding sides, such, for example, as knives and scissors.

Another object of my invention is to provide a grinder in which the grindstone is self-dressing.

In the accompanying drawing, Fig. 1 illustrates a side view, partly in section, of a grinder built in accordance with my invention; Fig. 2 illustrates a top view thereof, also partly in section; Fig. 3 is a vertical sectional view looking in direction of the arrow on line 3—3 in Fig. 1; Fig. 4 is a perspective view of the guiding member, and Fig. 5 is a modification of the guiding member.

Referring to the drawing in detail, Fig. 1 illustrates an electric motor, the windings and magnetic core of which are not shown and form no part of this invention, enclosed in a casing 5, having a base 6 and a sleeve section 7 at the top. The motor is provided with a shaft 8 which is guided by an upper bearing 9 and a lower bearing 10. The lower bearing is mounted in the end wall 11 of the casing 5. The thrust of the shaft 8 is taken up by a ball 12 resting on a plate 13 in a recess 14 provided in the end wall 11.

On the upper end of shaft 8 a collar 15 is mounted by means of a set screw 16. A grindstone 17 in the form of a ring is cemented to this collar. The collar is mounted on the shaft in a position such that the stone 17 will project partly above the end of sleeve 7. The sleeve 7 is threaded on the outer side to receive a cap or guiding member 18, which is a cover for the sleeve and encloses the stone.

The cap 18 is a cup-shaped member provided with a pair of parallel slots 19 and 20. These slots are spaced slightly from the axis of the stone so that they are substantially radial with respect to the stone. Each slot is bounded by sides 21 and 22. The side 22 being at a slight angle to the vertical is designed to guide the inner edge of scissors and the side 21 is at a slight angle to the horizontal which is the proper angle at which to guide knives. The slots do not extend across the entire diameter of the cap 18. The material of the cap is cut away at each end of the slots and at right angles thereto leaving the surfaces 23 and 24 within a short distance

of the edge of the stone 17 and thereby permitting the guiding of the knives and scissors within a short distance of the handle or, in the case of scissors, within a short distance of the pivot pin. This cutting of the cap leaves a cross bar 25 at the top to cover the stone. This bar is provided with a lug 26 attached thereto in a manner to project into the center of the grindstone. This lug prevents the drawing of the point of a knife in under the bar 25 when the stone is operating at high speed.

Another important feature in the use of grindstones is the provision of means to keep the grinding surface flat. This is generally accomplished by a separate tool, the use of which in a home is objectionable. In accordance with my invention I guide the edge to be sharpened over the face of the stone in such a manner that the pressure is substantially equal over the grinding surface and the surface is thereby worn off equally. The term used for flattening a grindstone surface is "dressing". In the apparatus described this is done automatically and we may say for convenience that the grindstone is self-dressing. I accomplish this automatic dressing by raising the one end of the guide slot whereby the slot is tilted at a slight angle to the horizontal plane of rotation of the grinding wheel so that the edge to be ground will contact the grinding wheel on only one side of the axis of rotation as clearly illustrated in Fig. 3. The grinding surface is also tilted somewhat so as to be parallel to the guide surface. As the cutting edge is guided over the surface, it is guided substantially parallel to this surface and thereby wears off the grinding surface equally wherefore separate resurfacing operations become unnecessary.

The cap 18 is adjusted with respect to the grinding surface by merely turning the cap on the sleeve and locking it in place by means of the locking ring 27. In Fig. 5 I have shown a modification wherein the cap is simply slipped over the sleeve 7 and is locked thereto by a screw 28. A slanting slot 29 in the cap provides for an adjustment of the cap and guide slots with respect to the grindstone surface.

Although I have described my invention in connection with the grinding of knives and scissors, it will be clear to those skilled in the art that it may be applied to the grinding of any edged tool. The knife and scissors illustrate merely two types of cutting edges, the scissors being the shearing edge and the knife the slicing edge. By merely selecting the proper angles to the two sides of the guiding slot, the grinder may be

adapted for the grinding of any type of cutting edge or it may be used merely for grinding any surface at a predetermined angular relation to a second surface.

5 What I claim as new and desire to secure by Letters Patent of the United States is:

1. In a cutlery grinding apparatus, the combination of a motor provided with a casing, and a shaft projecting therefrom, a grinding wheel mounted on said shaft, an adjustable cover for said casing and wheel provided with a guide slot arranged substantially radially to said grinding wheel and provided with two sides, each of which is arranged at a predetermined angle to the wheel

surface for respectively guiding tools having cutting edges formed by two surfaces at different angles to each other.

2. In a cutlery grinding apparatus, the combination of a motor provided with a casing and a shaft projecting above said casing, a grindstone mounted on said projecting shaft, and a cover for said casing enclosing said grindstone and provided with a guide slot having sides arranged angularly with respect to said grindstone, the angular relations of said sides being selected for guiding tools having shearing and slicing edges respectively.

NATHAN H. ADAMS.
